UNITED STATES PATENT OFFICE.

J. THOMAS LEE, OF MATTOON, ILLINOIS.

FEED-WATER HEATER.

SPECIFICATION forming part of Letters Patent No. 393,375, dated November 27, 1888.

Application filed February 27, 1888. Serial No. 265,414. (No model.)

To all whom it may concern:

Be it known that I, JULIUS THOMAS LEE, of Mattoon, in the county of Coles and State of Illinois, have invented a new and Improved 5 Feed-Water Heater and Purifier for Locomotive-Boilers, of which the following is a full, clear, and exact description.

The object of the invention is to provide a new and improved feed-water heater and water-purifier in which the escaping smoke and gases of the boiler and the exhaust-steam of the locomotive-engines furnish the necessary heat.

The invention consists of a water-jacket diaphragm or heat-deflector held in the smoke-box of the boiler and connected with an injector or pump, and of a water-jacket surrounding the stand-pipe and connected with the said water-jacket diaphragm and also with the interior of the boiler.

20 The invention also consists of certain parts and details and combinations of the same, as will be fully described hereinafter, and then pointed out in the claims.

Reference is to be had to the accompanying 25 drawings, forming a part of this specification, in which similar letters of reference indicate corresponding parts in all the figures.

Figure 1 is a longitudinal sectional elevation of the improvement as applied. Fig. 2 30 is a sectional end elevation of the same on the line *x x* of Fig. 1; and Fig. 3 is a like view of the same on the line *y y* of Fig. 1.

The locomotive boiler A, of any approved construction, is provided with the usual steam-space, B, and the flues C, which pass through the flue-sheet D at the rear end of the boiler A, and open into the smoke-box E, carrying the usual smoke-stack, F. In the smoke-box E is secured a stand-pipe, G, of any approved 35 construction, and connected in the usual manner with the cylinders H H of the locomotive-engines. The stand-pipe G may terminate below the lower end of the smoke-stack F, or 40 may extend into the latter to any desired height.

45 Between the stand-pipe G and the flue-sheet D is placed a transversely-extending water-jacket diaphragm or heat-deflector, I, secured by suitable means to the flue-sheet D and to 50 the shell of the smoke-box E. The bottom of the diaphragm I is formed in a zigzag line, as shown in Figs. 2 and 3, and from the lowest

points of the zigzag extend downward the outlet-pipes J, which pass through the shell of the smoke-box E and open at their lower outer ends into a mud-drum, J', held transversely under the smoke-box E and provided with an outlet-valve, J'', operated by suitable levers and links, J', from the cab of the locomotive, so that when the engineer desires he can open 60 or close said valve J''. The mud-drum is also provided with removable heads for cleaning the mud-drum whenever desired.

Near the bottom I' of the water-jacket diaphragm I discharge the pipes K, which extend through the smoke-box E in opposite directions, passing through the shell of the smoke-box E, and being provided at their outer ends with check-valves K'. From the latter extend pipes which lead to a suitable source of water-supply—such as an injector or pump—controlled by the engineer in the cab of the locomotive. From the upper end of the water-jacket diaphragm I lead the two pipes L L', which extend downward and discharge into a 70 four-way connection, L'', connected by the pipe L' with the lower end of a water-jacket, N, formed around the stand-pipe G. From the four-way connection L'' also extends a pipe, L', forward, passing through the front plate, 75 E', of the smoke-box E, and provided at its outer end with a cap, L''. The pipe L' serves to wash out and fill the boiler whenever desired.

From the upper end of the water-jacket N 80 lead the pipes O O, which pass through the smoke-box E and through the flue-sheet D into the steam-space B of the boiler A. The inner downwardly-extending end of each pipe O is provided with a bell, P, which extends at its 85 lower end to within a short distance of the upper row of flues, C. The pipes Q (shown in Fig. 1) are the usual steam-supply pipes for the engine cylinders. From the water-jacket N leads a pipe, N', connecting with one of the 90 discharge-pipes J, above mentioned.

The operation is as follows: The feed-water necessary to supply the boiler A passes from the injector or pump to the check-valves K' and from the latter to the pipes K, to be discharged into the water-jacket diaphragm I. As the latter is exposed to the heat from the escaping steam and gases of the fire-box and flues, the water in the same becomes heated to 100

a certain extent, and the heated water in the water-jacket diaphragm I is taken from the top of the latter by the pipes L L', passing through the four-way connection L², the pipe 5 L', and into the water-jacket N, surrounding the stand-pipe G. The exhaust-steam from the cylinders H H passes up through the stand-pipe G, heats the same, and also imparts considerable heat to the water contained in the 10 jacket N, surrounding the said stand-pipe G. The water in the water-jacket N is heated to nearly the boiling-point and passes from the upper end of the said jacket N through the pipes O into the interior of the boiler A, so that 15 the feed-water has nearly the same temperature as the water already in the boiler A. It will be seen that the exterior surface of the jacket N is also exposed to the heat of the waste gases and smoke of the fire-box and flues C, as the 20 said gases and smoke pass from the outside of the water-jacket diaphragm I through the smoke-box E to the smoke-stack F, and out of the latter to the open air in the usual manner. The water-jacket diaphragm I and the water- 25 jacket N are always filled with water, and consequently the water is not subjected to much motion on account of the starting motion of the locomotive, so that the sediment contained in the water and passing into the water-jacket 30 diaphragm I settles in the zigzag bottom of the latter and passes through the pipes J into the mud-drum J', from which it can be drained off at any time by the engineer in charge of the locomotive whenever the said engineer opens 35 the valve J², whereby the sediment collected in the mud-drum J' passes out through the valve J². If any sediment has collected in the water-jacket N, said sediment will be drained off at the same time through the pipe N', which 40 connects with one of the pipes J, as before mentioned. Thus it will be seen that the feed-water is not only heated to a high degree, but also passes in a purified state into the boiler A, as the sediment contained in the water is 45 drained off, as aforesaid. Light and foamy sediment, which passes from the water-jacket N through the pipes O into the boiler A, is held and accumulates in the bell P of the said pipes O, so that when the engineer opens the 50 valve J² the sudden pressure and reaction from the boiler A will force said light foamy sediment back through the pipe O into the water-jacket N, and from the latter through the pipes N' into the respective pipe J and into the mud- 55 drum J', and from the latter through the valve J² to the outside.

Having thus fully described my invention, I claim as new and desire to secure by Letters Patent—

60 1. In a feed-water heater for locomotive-boilers, the combination, with a water-jacket diaphragm or heat-deflector held in the smoke-box of the boiler and connected with a water-supply, of a water-jacket surrounding the stand-pipe and connected with the said water-jacket diaphragm and also with the interior of the boiler, substantially as shown and described.

2. In a feed-water heater for locomotive-boilers, the combination, with a water-jacket diaphragm held in the smoke-box of the boiler 70 and connected with the water-supply and provided with a zigzag bottom, of pipes leading from the lower angles of the said zigzag bottom and extending to the outside of the smoke-box, substantially as shown and described. 75

3. In a feed-water heater for locomotive-boilers, the combination, with a water-jacket diaphragm held in the smoke-box of the boiler and connected with the water-supply, said water-jacket diaphragm being provided with a 80 zigzag bottom, of pipes leading from the lowest points of the said zigzag bottom downward and out of the said smoke-box, a mud-drum in which discharge the said pipes, and an outlet-valve from the said mud-drum and operated 85 from the cab of the locomotive, substantially as shown and described.

4. In a feed-water heater for locomotive-boilers, the combination, with a water-jacket diaphragm, held in the smoke-box of the 90 boiler and connected with the water-supply, said water-jacket diaphragm being provided with a zigzag bottom, of pipes leading from the lowest points of the said zigzag bottom downward and out of the said smoke-box, a 95 mud-drum in which discharge the said pipes, an outlet-valve from the said mud-drum and operated from the cab of the locomotive, and a water-jacket surrounding the stand-pipe in the smoke-arch and connected with the said water-jacket diaphragm, and with one of the said pipes extending from the zigzag bottom of the water-jacket diaphragm, substantially as 100 shown and described.

5. In a feed-water heater for locomotive-boilers, the combination, with a water-jacket diaphragm held in the smoke-box of the boiler and connected with the water-supply, said water-jacket diaphragm being provided with a zigzag bottom, of pipes leading from the 105 lowest points of the zigzag bottom downward and out of the said smoke-box, a mud-drum in which discharge the said pipes, an outlet-valve held on the said mud-drum and operated from the cab of the locomotive, a water-jacket surrounding the stand-pipe in the smoke-arch and connected with the said water-jacket diaphragm and with one of the said pipes extending from the zigzag bottom of the water-jacket diaphragm, and pipes leading 110 115 from the said water-jacket to the interior of the said boiler, substantially as shown and described. 120

6. In a feed-water heater for locomotive-boilers, the combination, with a boiler provided with boiler-flues, stand-pipe, and smoke-box, of a water-jacket diaphragm held in the said smoke-box and exposed to the action of the waste gases and smoke of the said boiler, a water-jacket formed around the said stand-pipe 125 130 and connected with the said water-jacket diaphragm, pipes leading from the upper end of the said water-jacket into the interior of the said boiler, and a bell held at the inner end

of each of the said pipes, substantially as shown and described.

7. In a feed-water heater for locomotive-boilers, the combination, with a locomotive-boiler provided with boiler-flues, a smoke-box and smoke stack, of a water-jacket diaphragm held in the said smoke-box and exposed to the action of the escaping smoke and gases of the said boiler, said water-jacket diaphragm being provided with a zigzag bottom, pipes leading from the said zigzag bottom to the outside of the said smoke-box, a mud-drum into which discharge the said pipes, an outlet-valve held on the said mud-drum and operated from the cab of the locomotive, a

water-jacket surrounding the stand-pipe and connected with the said water-jacket diaphragm, and also connected with one of the outlet-pipes of the said water-jacket diaphragm, pipes leading from the upper end of 20 the said water-jacket and extending into the interior of the said boiler, and bell-shaped funnels formed on the inner ends of the said pipes directly above the said boiler-flues, substantially as shown and described.
